UNITED STATES PATENT OFFICE.

LILLIAN M. BOLING, OF HENDERSONVILLE, NORTH CAROLINA.

GARMENT HANGER.

Application filed April 22, 1924. Serial No. 708,167.

This invention relates to improvements in garment hangers and more particularly to a hanger especially designed for retaining ladies' dresses.

5 An important object of the invention is to provide a garment hanger having retaining means thereon to prevent the displacement of the garment from the support bar.

10 A further object of the invention is the provision of a hanger of this character adapted to support delicate garments without danger of tearing or materially marking the same.

15 A still further object of the invention is to provide a hanger of this character which is simple in construction, durable, and efficient for the purpose intended.

20 Other objects and advantages of this invention will be apparent during the course of the following description.

In the accompanying drawing forming a part of this specification and in which like numerals are employed to designate like parts throughout the same:

25 Figure 1 is a side elevation of the device embodying my invention,

Figure 2 is a top plan view of the same,

Figure 3 is an enlarged sectional view taken on the line 3—3 of Figure 1, and

30 Figure 4 is an enlarged sectional view taken on the line 4—4 of Figure 2.

In the drawing, wherein for the purpose of illustration I have shown the preferred embodiment of my invention, the numeral 35 5 designates the support bar which is of common design and may be constructed of wood, aluminium or other suitable material. The central portion of the support bar 5 is provided with a vertical bore adapted to receive the lower extension of a hook 6, the lower extremity having a nut 7 threadedly mounted thereon to prevent removal of the hook. Mounted upon the sides of the support bar 5 adjacent the hook 6 are two pairs

40 45 of flange plates 8 provided near the lower extremities with pointed extensions 9 and having openings formed therein for the purpose of permitting retaining screws 10 to be inserted therethrough and secure the

50 55 same to the support bar. The pointed extensions 9 are to be forced to the side of the support bar and prevent rotation of the flange plates. The upper extremity of the flange plates are also provided with openings to receive a transverse bolt 11 rotatably mounted within the said openings and pre-

vented from displacement by a nut 12. Mounted longitudinally upon the support bar and secured to the upper portion of the bolts 11 are a pair of spring arms 13 secured 60 to the bolts 11 by solder or the like and retained normally against the support bar by means of a spring 14 engaging one extremity of the spring arm and fastened about the flange plates. The spring arms 13 as 65 shown in Figure 1 are comprised of comparatively short actuating extensions 15 extending toward the center of the support bar. The comparatively long extension or clamping portion comprises an upwardly extending curved portion 16 extending downwardly and toward the extremities of the support bar, the extremity being bent to form a loop 17 presenting a smooth engaging 70 surface.

75 In use, the device is particularly adapted for light and delicate garments which may be placed upon the support bar while the spring arms 13 are in the raised position and after the garment is correctly placed upon the bar the spring arms are permitted to assume their normal position upon the support bar, thus retaining the garment upon the bar and preventing displacement of the same. It is well known 80 that garments, particularly ladies' gowns, are often badly damaged by falling from the hanger upon which they are positioned. It is especially noticeable in establishments handling ladies' gowns and the like where 85 it often happens that the delicate fabrics are practically ruined by falling upon the floor. With my improved device it is obvious that the garments will be retained upon the hangers and prevented from falling thus greatly preserving the appearance 90 of the garment and preventing losses due to removal of the garment.

95 It is to be understood that the form of my invention herewith shown and described is to be taken as the preferred example of the same, and that various changes as to the shape, size and arrangement of parts may be resorted to without departing from the spirit of the invention, or the scope of the 100 subjoined claim.

105 Having thus described my invention, I claim:

A garment hanger comprising a bar, plates mounted at the opposite sides of the bar, a bolt carried by the plates and bridging the space between them and being

spaced above the surface of the bar, a resilient arm fixed to the bolt and lying between the plates, a spring mounted at its end portions upon the plates at points between the 5 bar and the bolt and having its intermediate portion bearing against the under side of the arm at a point beyond one side edge

of the plates, the intermediate portion of the arm at a point beyond the opposite side edges of the plates being upwardly 10 bowed.

In testimony whereof, I have affixed my signature.

LILLIAN M. BOLING.
